UNITED STATES PATENT OFFICE.

PAUL FREDRICK LUETH, OF EVERETT, WASHINGTON, ASSIGNOR TO SUMNER IRON WORKS, OF EVERETT, WASHINGTON, A CORPORATION OF WASHINGTON.

SAWMILL CARRIAGE.

Application filed June 14, 1924. Serial No. 720,053.

This invention relates to saw mill carriages, and particularly to mechanism designed to facilitate the proper positioning of logs on the carriage, as well as to assist 5 in the transfer of the logs to and from the same.

In the method of sawing logs, which is at present almost invariably used, in order to permit the least possible waste of material 10 in sawing the log, the latter is so positioned on the carriage as to cause the saw to travel through the same in a plane parallel to the outside line of the log, instead of parallel to its center line. Since the knees are 15 usually connected rigidly to the setting mechanism, it is necessary to introduce some other means for bringing the small end of the log up ahead of the face of the knees a distance equal to the amount of taper in 20 the log. This has usually been accomplished by a crude and cumbersome method of interposing wooden spacer blocks between the face of the knee and the log, which blocks were of sufficient thickness to allow for the 25 taper of the log. This is an expensive method owing to the amount of time required in securing a block of the right thickness, and also because of the time and material required in making these spacer blocks, which 30 are necessarily short lived and therefore required in great numbers. This method is also very dangerous to the operator.

One of the principal objects of the present invention is to provide an improved tapering device, preferably power operated, 35 which is movable with respect to the knee, and by means of which the proper taper may be quickly and accurately secured by making the proper adjustment either before or after 40 the log has been rolled on the carriage.

Another important object is to provide a buffer, cushioned preferably by pneumatic means, for taking up the shock of the log as it is rolled on the carriage or canted by 45 the nigger or canting gear, thus eliminating the danger of breaking or otherwise injuring the knees, and prolonging the life thereof indefinitely.

A further object is to provide means for 50 quickly kicking the log or cant from the carriage, thereby eliminating the slow process now used in which it is necessary to run the faces of the knees to the extreme out position on the blocks by means of the setting mechanism.

The mechanism for accomplishing the foregoing advantages is embodied in a unitary device, which is simple and inexpensive, positive in its results, and which may be installed on any type of head block now 60 in use with only slight expense in adapting the same.

In carrying out the invention, the knee is made hollow, but is otherwise the same as those now in use, and may bear the same 65 relation to the head block and carriage. Within this hollow space, which extends longitudinally of the knee, is guided a ram, which may be operated by air, steam or other fluid or power. This ram may be projected beyond the face of the knee and positively held in the proper position to form a taper for the log, or it may be pneumatically held in its projected position to form a buffer 70 when moving the log into position. By 75 forcibly projecting the ram, the end of the log may, if necessary, be set out after the log is on the carriage, and by projecting the rams simultaneously to the fullest extent, the device may be operated as a kicker to 80 remove the cant from the carriage.

The advantages of the invention as well as its details of construction will be more clearly understood from the following detailed description taken in connection with 85 the accompanying drawings, which illustrate the invention in its preferred form.

In the drawings:

Figure 1 is a perspective view of a carriage with a screw operated head block constructed according to the invention.

Figure 2 is a perspective view of the head block from another angle.

Figure 3 is a longitudinal vertical section through the knee, with a portion of the head block shown in elevation.

Figure 4 is a horizontal section through the piston and valve, taken on the line 4—4 of Figure 3.

Figure 5 is a vertical section through the valve taken on the line 5—5 of Figure 4.

Figure 6 is an end view of the cylinder and valve casing, a part thereof being shown in section.

Figure 7 is a side elevation of the valve casing, looking from the line 7—7 of Figure 4.

Figure 8 is an end view of the valve casing, with a part thereof shown in section.

Figure 9 is a horizontal section through the side of the valve casing, showing the inlet and exhaust ports.

Figure 10 is an end view of the hose reel.

5 Figure 11 is a view partly in elevation and partly in section, looking from the right of Figure 10.

Figure 12 is a sectional view of the air connection for the hose reel.

10 Figure 13 is a detail sectional view, taken axially through the cam which controls the pawl for positioning the ram.

Figure 14 is a detail perspective view of the cam.

15 Figure 15 is a detail perspective view of the hand lever socket for manually operating the ram.

Figure 16 is a detail perspective view of the pawl.

20 Figure 17 is a detail perspective view of the valve operating lever.

For the sake of illustrating the structure and operation of my invention, I have shown it in connection with a carriage 1 of usual structure having head blocks 2 provided with guideways 3, on which the knee 4 is reciprocably mounted. In the type of machine shown, this reciprocation is effected through the medium of bevelled gears 5, 30 operated by a power shaft 6.

In this invention, the knee 4 differs from the usual construction by being hollow and having a rectangular opening through the front face which forms a guideway 7, in 35 which a ram 8 is mounted for reciprocation. This ram is formed at its rear end with a reduced portion 9 extending through the rear face of the knee, and provided at its rear end with a piston 10 having the 40 usual rings 11. The piston operates within a cylinder 12 which is provided with a peripheral flange 13, which is secured to the rear face of the knee by means of bolts 14, or the like. The rear wall of the knee has 45 a depressed portion 15 surrounding the rearwardly extended portion 9 of the ram, and receives suitable packing rings 16, which form an air-tight connection between the knee and cylinder 12. The ram is preferably 50 made hollow, and its inner extremity is closed by a suitable plug 17. (Fig. 3.)

The ram 8 is adapted to be projected from the front face of the knee, and for holding it in various positions when used as a tapering device a central web is formed therein and provided with a plurality of stepped notches 18 for engagement by a gravity pawl or stop latch 19, which is pivotally mounted on a pin 20 extending transversely across 55 the rear upper portion of the knee. In order to fix the position of the pawl so as to engage any one of the notches 18, the same is provided with a rearward flat-faced extension 21, the upper face of which is adapted 60 to be engaged by a cam 22 secured to a rock

shaft 23. The cam 22 is provided with a plurality of flat faces 24 at different distances from its axis, and the rock shaft 23 is extended at one end beyond the side of the knee and provided with a lever arm 25, by 70 means of which it may be angularly adjusted to bring any one of the faces 24 into engagement with the extension 21, and thereby adjust the pawl 19 for engagement with the desired notch 18. (Figs. 2 and 3.)

The position of the ram 8 and its movement in either direction is controlled preferably through the piston 10 by means of compressed air, steam or other fluid introduced into either end of the cylinder 12 through a 80 hose 26 and valve casing 27. (Figures 2 and 4.) The valve casing is provided with a flange 27^a, which cooperates with a similar flange 27^b formed on the side of the cylinder 12, (Fig. 7) to secure the valve casing in 85 operative relation to the ports in the cylinder. The cylinder is provided at or near its ends with inlet ports 28 and 29 and exhaust ports 30 and 31, and the passage of the steam or air therethrough is controlled by a valve 90 32 operating within the casing 27. The valve 32 is in the shape of a piston secured to a stem 32^a and formed with an intermediate reduced portion which, when the valve is in neutral position, is opposite the central 95 portion of the chamber 33, which is connected to the supply pipe 26. Movement of the valve to the left or right, however, will establish communication between the chamber 33 and one of the passageways or ports 100 34 or 35, (Fig. 5) which are in communication with the inlet ports 28 and 29 respectively. The rate of admission of the operating fluid through the ports 34 and 35 may be controlled by means of choker screws 36. 105 As the valve 32 is moved to place the chamber 33 in communication with one or the other of the inlet ports, the exhaust port leading from the opposite end of the cylinder is at the same time placed in communication with the corresponding exhaust port 110 37 or 38 in the valve casing, (Fig. 5) which is uncovered by the end of the valve. The ports 37 and 38 are in communication with an exhaust pipe 39 leading to any convenient 115 point of discharge. The ends of the valve casing 27 are closed by suitable packing rings 40 and 41 through which the stem 32^a projects, and the valve is normally held in neutral position, as shown in Figures 4 and 120 5, by means of a spring 42 which surrounds the valve stem within the housing 43, and acts between the packing ring 40 and a head 44 secured to the valve stem.

For actuating the valve in either direction, one end of the stem 32^a is pivotally connected to the lower end of an arm 45 secured to one end of a rock shaft 46, which is journaled in a plate 47 secured to the outer end of the cylinder 12. To the op- 125

posite end of the rock shaft 26 an actuating arm or lever 48 is secured. The arm 48 has a downward extension 49, which is engageable by a tappet pin 50 movable longitudinally within the tappet sleeve 51, and actuated by the piston 10 at the outer limit of its stroke for a purpose which will be hereinafter explained. (Figs. 5 and 6.)

The hose 26, through which the steam or air pressure is introduced into the cylinder, is so mounted as to be longitudinally extensible to allow for the lateral adjustment of the knee. To this end it is preferred to mount the hose on a reel 52, which is secured 15 to a rotatable shaft 53 and provided with a peripheral spiral groove 54 in which the hose is adapted to be wound. (Figs. 2, 10 and 11.) At one end of the groove 54, an angular nipple 55 is secured and adapted to 20 be connected with one end of the hose 26. The inner end of the nipple 55 is secured in a socket 56 leading to a recess or bore 57 in one end of the shaft 53. Revolubly secured in this recess is a nipple 58, which may 25 be connected to the pipe line. The nipple 58 is revolubly secured to the end of the shaft 53 by means of a sleeve 59 having an enlarged outer end in which is threaded a collar 60 which secures a packing ring or 30 gasket 61 between its inner face and a flange 62 formed on the nipple 58. Thus, a tight joint is secured which permits free rotation of the shaft 53. (Fig. 12.)

Since it may at times be desirable to operate the ram 8 manually, I prefer to mount a lever 63 on a pin 64 extending across an opening 65 formed in the upper side of the knee 4. This lever 63 is provided with a socket 66 for receiving a lever bar, and the 40 lever extends downwardly, as at 67, through a slot 68 in the pawl 19 and engages a slot 69 formed in the ram, whereby the latter may be reciprocated manually whenever desired.

When the invention is to be used as a power tapering device, the cam 22 is rotated by means of the lever 25, so that the pawl 19 will be in position to engage the desired notch 18, which will produce the desired 50 distance between the face of the ram 8 and the face of the knee 4. In practice the notches 18 are usually arranged so as to set out the ram 8 two, four or six inches, and when the ram 8 is fully extended there is a distance of 55 ten inches between its outer face and the face of the knee. After the cam 22 has been properly set, the lever 48 is moved forwardly so as to move the valve 32 rearwardly and place the pressure chamber 33 into communication with the ports 35 and 29, and to advance the piston 10 and the ram 8. As soon 60 as the ram has been extended sufficiently for the point of the pawl 19 to drop in the desired notch 18, the lever 48 is reversed so 65 as to admit pressure through the port 28, and

to connect the port 30 with the exhaust pipe 39. The face of the ram 8 is now held firmly in the desired position, so as to produce the taper desired.

In operating the device as a kicker, the lever 48 is moved forwardly and held there, while the ram 8 is projected to its full extent to kick the cant from the carriage. Upon reversing the position of the lever 48, the ram will be restored to its former position. 75

In using the device as a buffer, the ram is projected to its full extent as when kicking off the cant, but is held there until the new log is rolled onto the carriage, the pressure 80 being retained in the rear end of the cylinder 12 to act as a cushion against the shock of the log, when it strikes the end of the ram. After the cam 22 has been previously set for the desired taper, the lever 48 may be 85 reversed and will leave the ram in the desired position. If a further tapering adjustment is desired it may be secured in the manner above explained.

In connection with the operation of the device as a kicker or buffer, it is to be noted that after the ram has been fully projected, upon releasing the lever 48 the recoil of the spring 42 will move the valve 32 to its extreme left hand position, and pressure will 90 be admitted through the port 28 to the left hand end of the cylinder. If the pawl 19 at this time is raised to its uppermost position, the ram will be completely retracted, and the piston 10 will be carried to the right hand end of the cylinder and will strike the tappet pin 50, rocking the shaft 46 sufficiently to 95 restore the valve to its neutral position. The valve will remain in this position until such time as the lever 48 is again moved forwardly. 100

From the foregoing description, it will be understood that the invention has a three-fold function, and may be operated either as a buffer, a kicker, or a tapering device depending upon the manner in which the levers 25 and 48 are manipulated. The invention is simple and inexpensive, and positive in its results. It reduces the expense 110 and conserves the life of the machine, and eliminates the waste of time and the danger in blocking the log by hand, and greatly facilitates the transfer of logs to and from the carriage. 115

While I have shown the detailed construction of one form in which the invention may be embodied, it will be understood that this is capable of many modifications, and that the invention is equally well adapted for use 120 in connection with other types of sawing machines. It is my intention, therefore, to include all such modifications within the scope of the appended claims. 125

What is claimed is:

1. In a saw mill carriage, the combination 130

of an adjustable hollow knee, a ram adapted to be housed therein, means operable by fluid pressure for projecting or retracting said ram, and means for securing the ram in various positions of adjustment.

2. In a saw mill carriage, the combination of an adjustable knee having a longitudinal guideway therethrough, a ram mounted in said guideway, means operable by fluid pressure for projecting and retracting the ram, and means for adjustably limiting the extent of retraction.

3. In a saw mill carriage, the combination of an adjustable knee having a longitudinal guideway therethrough, a ram mounted in said guideway, and means operable by fluid pressure for projecting or retracting the ram.

4. In a saw mill carriage, the combination of an adjustable knee having a longitudinal guideway therethrough, a ram mounted in said guideway, a piston carried by the rear end of the ram, a cylinder in which the piston is guided, and means for selectively introducing fluid pressure into either end of the cylinder and simultaneously exhausting the other end.

5. In a saw mill carriage, the combination of a knee having a recess therein, a ram mounted for reciprocation in said recess, a piston secured directly to the rear end of the ram, a cylinder in which the piston is guided, means for selectively introducing fluid pressure into either end of the cylinder and simultaneously exhausting the other end, and adjustable stop mechanism for positively limiting the rearward movement of the ram.

6. In a saw mill carriage, the combination of a hollow knee, a ram projectable therefrom, means operable by fluid pressure to project the ram to kick off the cant, to hold the same in projected position to act as a buffer, or to retract the ram, and a latch cooperating with the fluid pressure means, to hold the ram in a partly retracted position to act as a taper device.

7. In a saw mill carriage, the combination of an adjustable knee having a longitudinal guideway therethrough, a ram mounted in said guideway, means operable by fluid pressure for projecting or retracting the ram, a manually operable lever pivoted to the knee, and engaging the ram to advance or retract the same in the absence of fluid pressure.

8. In a saw mill carriage, the combination of a hollow knee, a ram adapted to be housed therein, means for advancing and retracting the ram, said ram being provided on its upper side with rearwardly facing stepped notches, a gravity pawl mounted above the ram, and adjustable means to limit the movement of the pawl under the influence of gravity to a position in the path of any selected one of said notches, whereby to posi-

tively stop the retractive movement of the ram at a predetermined point.

9. In a saw mill carriage, the combination of a knee having a guideway, a ram mounted for reciprocation in the guideway, means for advancing or retracting the ram, said ram being provided with rearwardly facing stepped notches, a gravity pawl pivoted within the knee and having a flat faced portion extending rearwardly from its pivot, a cam rotatably mounted above the rearwardly extending portion of the pawl and having a plurality of flat faces at different distances from its axis, and means for adjusting the cam to cause any one of its faces to engage the flat faced portion of the pawl, thereby positioning the pawl in the path of a selected one of said notches to limit the rearward movement of the ram.

10. In a saw mill carriage, the combination of a hollow knee, a ram mounted for reciprocation therein, means operable by fluid pressure for advancing or retracting the ram, a valve controlling said fluid pressure, and means automatically operable by the ram when fully retracted to restore the valve to neutral position.

11. In a saw mill carriage, the combination of a guideway, a ram mounted for reciprocation therein and formed at its rear end with a piston, a cylinder within which said piston operates, a valve controlling the admission of fluid pressure into either end of the cylinder, and means operated by the piston when the ram is fully retracted to restore the valve to neutral position.

12. In a saw mill carriage, the combination of a guideway having a ram mounted for reciprocation therein, said ram being formed at its rear end with a piston, a cylinder within which the piston operates, a valve controlling the admission of fluid pressure into either end of the cylinder, a lever for operating the valve, and a tappet pin in the end of the cylinder and engageable by the piston when the ram is fully retracted to rock said lever and restore the valve to neutral position.

13. In a saw mill carriage, the combination of a guideway having a ram mounted for reciprocation therein, said ram being formed at its rear end with a piston, a cylinder within which the piston operates, a valve controlling the admission of fluid pressure into either end of the cylinder, a lever for operating the valve, and means operated by the piston when the ram is fully retracted to rock said lever and restore the valve to neutral position.

14. In combination with a saw mill carriage, a hollow knee, a ram carried thereby and projectable therefrom, means for operating the ram by fluid pressure, and means for positively stopping the retractive movement

- of said ram with its face at different distances from the face of the knee.
15. In combination with a saw mill carriage, a hollow knee, a ram carried thereby and projectable from the face of the knee at different distances, fluid pressure operated means for projecting and retracting the ram, and a stop latch for holding the ram at different points of adjustment.
- 10 16. In combination with a saw mill carriage, a hollow knee, a ram carried thereby and projectable therefrom, means for operating the ram by fluid pressure, means for positively stopping the retractive movement of said ram with its face at different distances from the face of the knee, a self-centering valve for controlling the fluid pres-
- sure, and a lever for operating the valve in either direction.
17. In combination with a saw mill carriage, a hollow knee, a ram carried thereby and projectable therefrom, means operable by fluid pressure to project and retract the ram, means for positively stopping the retractive movement of the ram with its face 25 at different distances from the face of the knee, a self-centering valve for controlling the fluid pressure, and a lever for operating the valve in either direction, the movement of the lever in one direction being controlled 30 by the rearward movement of the ram.

In testimony, that I claim the foregoing as my own, I have hereto affixed my signature.

PAUL FREDRICK LUETH.
